OIL BURNING RANGE FOR HEATING AND COOKING

Frank H. Schneider, Spring City, Pa.

Application December 10, 1934, Serial No. 756,746

6 Claims. (Cl. 126—44)

In the design for an oil burning range for heating and cooking many factors have to be taken into consideration which are not material in the design of a gas range. Among these factors are the following: The discharge flue of the range must be connected with the chimney to carry off the waste products of combustion. The flue construction should provide for the passing of the flue gasses directly to the bottom of the oven. A minimum of draft should be used to prevent an excess amount of heat passing into the discharge flue of the range. An individual burner assembly should be provided for oven heating and for top cooking and provision made for also using the oven burner for top cooking. The walls should be insulated so that the range will be efficient and comfortable in hot weather. The doors and coveralls should be arranged so that when open a maximum of room heating can be obtained in cold weather. Provision for broiling by the radiant heat energy of the flame, where it is hottest should also be present.

In my present invention proper consideration has been given to these features to produce an oil burning range which will be efficient and economical for room heating and for cooking.

My invention, therefore comprehends a novel oil burning range, wherein the heat from the oven burner first heats the bottom of the oven, then passes around the sides and top to the discharge flue so that a minimum of draft is required to operate the burner.

It further comprehends a novel construction and arrangement of burners, ovens, and flue passages.

It further comprehends novel means to enable one to use the radiant heat energy of the flame for broiling.

Other novel features of construction and advantage will hereinafter appear in the detailed description and the appended claims.

For the purpose of illustrating the invention, I have shown in the accompanying drawings typical embodiments of it, which, in practice, will give satisfactory and reliable results. It is, however, to be understood that the various instrumentalities of which my invention consists can be variously arranged and organized and my invention is not limited to the exact arrangement and organization of these instrumentalities as herein set forth.

Figure 1 is a perspective view of an oil burning range embodying my invention.

Figure 2 is a section thereof, the section being taken substantially on line 2—2 of Figure 1.

Figure 3 is a section on line 3—3 of Figure 2.

Figure 4 is a section on line 4—4 of Figure 2.

Figure 5 is a section on line 5—5 of Figure 2.

Figure 6 is a section on line 6—6 of Figure 2.

Figure 7 is a section of another embodiment.

Similar numerals indicate corresponding parts. 5

Referring to the drawings:—

1 designates an oil burning range for heating and cooking embodying my invention. The body portion 2 of the range consists of double walls with insulation between them forming the bottom and side walls, which latter carry a cast iron top plate 3 for top cooking. The top plate has a desired number of pot receiving openings 4 and covers 5. 6 designates insulated coveralls hinged at their rear ends as at 7, see Figures 3 and 4. The coveralls can be raised against a balustrade 8.

The range is provided with an upper burner chamber 9 in which is located an upper oil burner 10 for top cooking, and with a lower burner chamber 11 provided with a lower oil burner 12. These burner chambers are separated from each other by an insulated wall 13. As illustrated, the range is provided with superimposed ovens 14 and 15, the upper of which forms a baking oven, and the lower of which forms a warming or broiling oven. An insulated wall 16 of the broiling oven forms a side wall of the lower burner chamber and merges into an upwardly inclined insulated top wall 17 which extends to the rear wall of the range and is spaced from the bottom wall of the baking oven to form a bottom flue 18 which leads from the lower burner chamber 11 above its burner 12. This flue 18 merges into an upwardly extending flue 19 between the side wall of the range and the side wall of the baking oven and merges into a laterally extending top flue 20 between the oven top and the top of the baking oven so that the top will be heated by heat from the lower burner. 30 A baffle 21 causes the products of combustion to pass in the direction of the arrows seen in Figure 5 to the discharge flue opening 22 leading to the discharge flue 23. The exit pipe 24 leads to the chimney and is provided with a 40 damper 25. A baffle 26 extends from the front wall to the rear wall, see Figure 5, to prevent heat from the upper burner passing to the top flue 20.

The top of the baking oven 14 is extended 50 downwardly to form a side wall of the upper burner chamber spaced from the juxtaposed side wall of the baking oven forming a heating space 26 which if desired may open as shown into the flue 18 but is closed at its top. 55

The bottom of the baking oven is preferably insulated as at 27.

The front wall of the range 28 is preferably of cast iron and has hinged to it an insulated door 29 for the upper burner chamber 9, an insulated door 30 for the lower burner chamber 11, an insulated oven door 31 for the baking oven 14, and an insulated door 32 for the broiling oven 15.

10 The top wall 17 of the broiling oven 15 has an opening 33 leading from the flue 18 and guides 34 are provided for an apertured plate 35 which is removable for cleaning.

When the broiling oven is not used an insulated 15 cover 58 may be placed in the opening 33.

The side wall of the burner chamber is provided with observation windows 36 and 37. 38 designates the oil reservoir having a line 39 leading to the upper burner and provided with 20 an oil level float valve 40. A line 41 from the oil reservoir to the lower burner is provided with an oil level float valve 42. The upper burner chamber has an air intake 43 and the lower burner chamber has an air intake 44.

25 Each oil burner is of the same construction and has an adjusting valve 45 and a lighting device 46.

Air intakes 47 and 48 are provided.

The range is mounted on legs 49 having any 30 conventional levelling devices 50.

51 is a heat reflecting baffle for the upper burner having an opening 52 for lighting the burner. 53 is a heat reflecting baffle for the lower burner having an opening 54 for lighting 35 the burner.

The oil burner for heating the baking oven can have any desired location so long as the heat is passed directly to the bottom of the oven to provide an even distribution of heat.

40 In Figure 7, the lower burner for the baking oven is positioned directly beneath the baking oven so that the products of combustion impinge against the insulated bottom of the baking oven which is of uniform thickness as at 55 instead of tapering in the direction of flow of the flue gasses so that in both cases there is a uniform distribution of heat over the bottom of the oven. An insulated wall 56 contributes to form a warming chamber 57.

50 If desired a hot water coil 59 may surround the top burner.

In order to increase the heating capacity of the range, I may employ pipes 60 having any desired arrangement in the upper burner chamber.

55 Cold air enters at the bottom, and the upper ends of the pipes terminate at a recess 61 in the top. The upper ends of the pipes may be controlled in any desired manner and for purpose of illustration I have shown a removable cover 60 62, flush with the range top.

The oil burners are of conventional construction and can be purchased in the open market. For convenience of illustration I have shown one upper and one lower oil burner but it is to be understood that each burner assembly may consist of one or more burners.

70 Due to the flue arrangement, a minimum of draft is required to operate the oil burners, as the products of combustion from the lower burner passes directly beneath the baking oven and the heat does not have to be drawn downwardly towards the bottom of the oven but has an upward travel.

75 The burner can be adjusted and lighted from

the front of the range by opening the burner doors.

One or both of the coveralls can be closed when using the baking oven.

When used for room heating, the radiant 5 heating energy from either burner can be utilized by opening the burner doors, and for additional heating the coveralls can be raised and the oven doors can be opened so that a maximum of room heating can be economically obtained. 10

It will now be apparent that I have devised a new and useful oil burning range for heating and cooking which embodies the features of advantage enumerated as desirable in the statement of the invention and the above description, 15 and while I have, in the present instance, shown and described preferred embodiments thereof which will give in practice satisfactory and reliable results, it is to be understood that these embodiments are susceptible of modification in 20 various particulars without departing from the spirit or scope of the invention or sacrificing any of its advantages.

Having thus described my invention what I 25 claim as new and desire to secure by Letters Patent is:—

1. In an oil burning range, a housing having means forming upper and lower burner chambers sealed from each other and having an exit flue near its top, a baking oven spaced from the walls 30 of the range to form a side flue merging into a top flue leading to the exit flue and spaced from the upper burner chamber to form a space closed at its top, a broiling oven vertically spaced from the baking oven to form a bottom flue leading 35 from the upper end of the lower burner chamber and at all times in free communication with said lower oil burner chamber, said space and said side flue, an oil burner in the upper burner chamber and an oil burner in the lower burner 40 chamber.

2. In an oil burning range, a housing having means forming upper and lower burner chambers sealed from each other and having an exit flue near its top, a baking oven spaced from the 45 walls of the range to form a side flue merging into a top flue leading to the exit flue and spaced from the upper burner chamber to form a space closed at its top, a broiling oven vertically spaced from the baking oven to form a bottom flue leading from the upper end of the lower burner chamber and at all times in free communication with said lower oil burner chamber, said space and said side flue, an oil burner in the upper burner chamber and an oil burner in the lower 55 burner chamber, the bottom of said baking oven having an insulated bottom progressively decreasing in thickness from said space to said side flue to provide uniform intensity of heat from said bottom flue throughout the area of 60 the bottom of the baking oven.

3. In an oil burning range, a housing having means forming upper and lower burner chambers sealed from each other and having an exit flue near its top, a baking oven spaced from the 65 walls of the range to form a side flue merging into a top flue leading to the exit flue and spaced from the upper burner chamber to form a space closed at its top, a broiling oven vertically spaced from the baking oven to form a bottom flue leading 70 from the upper end of the lower burner chamber and at all times in free communication with said lower oil burner chamber, said space and said side flue, an oil burner in the upper burner chamber, an oil burner in the lower burner 75

chamber, said broiling oven having its walls insulated and an opening in its top wall communicating with said bottom flue, and a removable insulated cover for said top opening.

- 5 4. In an oil burning range, a housing having a top cooking wall and having means forming upper and lower burner chambers sealed from each other and having an exit flue near its top, a baking oven spaced from the walls of the range 10 to form a side flue merging into a top flue leading to the exit flue beneath said top cooking wall and spaced from the upper burner chamber to form a space closed at its top, a broiling oven vertically spaced from the baking oven to form 15 a bottom flue leading from the upper end of the lower burner chamber and at all times in free communication with said lower burner chamber, said space and said side flue, an oil burner in the upper burner chamber, and an oil burner in the 20 lower burner chamber.
5. In an oil burning range, a housing having means forming upper and lower burner chambers sealed from each other and having an exit flue near its top, a baking oven spaced from the 25 walls of the range to form a side flue merging into a top flue leading to the exit flue and spaced from the upper burner chamber to form a space closed at its top, a broiling oven vertically spaced

from the baking oven to form a bottom flue leading from the upper end of the lower burner chamber and at all times in free communication with said lower burner chamber, said space and said side flue, an oil burner in the upper burner 5 chamber, an oil burner in the lower burner chamber, said burner chambers having door controlled openings, and baffles extending downwardly from above said openings towards the bottom of the burners to cause the air for 10 primary combustion to pass beneath the burners.

6. In an oil burning range, a housing having means forming upper and lower burner chambers sealed from each other and having an exit flue near its top in communication with the 15 upper burner chamber, a baking oven spaced from the range to form a side flue merging into a top flue leading to the exit flue and spaced from the upper burner chamber to form a space closed at its top, the bottom of said 20 baking oven contributing to form a bottom flue leading from the upper end of the lower burner chamber and at all times in free communication with said lower oil burner chamber, said space and said side flue, an oil burner in the upper 25 burner chamber and an oil burner in the lower burner chamber.

FRANK H. SCHNEIDER.
